UNITED STATES PATENT OFFICE.

CLEOPHAS DUMAIS, OF LIMOILOU, QUEBEC, CANADA.

SKI ATTACHMENT.

Application filed March 3, 1927. Serial No. 172,447.

The present invention relates to attachments for skis and has for its primary object to provide a device which will automatically engage the ground to prevent backward movement of the ski.

A further object of the invention is the provision of an attachment of the above character formed so as to be normally urged to a downward ground engaging position.

10 A still further object of the invention is to provide a ski attachment constructed so as to avoid displacement of the ground engaging member while in use.

15 Another object of the invention is the provision of a back slipping ski attachment which is simple and durable of construction and which will efficiently perform the function intended.

20 Other objects and advantages will be apparent as the description progresses.

In the accompanying drawings forming a part of this specification and in which like reference characters are employed to designate corresponding parts throughout the 25 same,

Figure 1 is a perspective view of a conventional type of ski showing my improved attachment mounted in operative position thereon;

30 Figure 2 is an enlarged side elevational view of the attachment in operative position;

Figure 3 is a vertical transverse sectional view taken on the line 3—3 of Figure 2;

35 Figure 4 is an enlarged perspective view of the assembled device; and

Figure 5 is an enlarged vertical sectional view taken on the line 5—5 of Figure 3.

Referring to the drawings wherein for the 40 purpose of illustration is shown a preferred embodiment of the invention, the numeral 10 generally designates a conventional type of ski embodying a longitudinal body having a vertical diminishing taper towards its rear end and formed with an upwardly curved front or toe portion 11. Secured on the intermediate portion of the ski body 10 is a foot pad 12. As will be readily understood by those familiar with the operation of skis, the wearer moves his legs forwardly and rearwardly in the simulation of walking so as to slide the skis over the ground. Each forward movement describes a step of forward progress while any rearward movement retards the progress. With this in mind, my invention contemplates the pro-

60 vision of an attachment adapted to be secured on the intermediate portion of the ski body immediately forward of the foot connection to prevent rearward movement of the skis so as to eliminate the lost motion occasioned thereby and at the same time the device is arranged so that little or no interference to the forward sliding movement of the ski will be effected.

65 With particular reference to the structure of my improved ski attachment the numeral 13 embodies a bracket member arranged for fixed connection on the ski, comprising an upright U-shaped bracket frame embodying vertically disposed side legs 14 offset laterally at their lower ends for extension at the side edges of the ski body. The intermediate portion of the frame embodies a longitudinal connecting bar 15 having its intermediate portion bent to form a U-shaped 70 tongue 16 directed at a rearward downwardly inclined position as clearly indicated in Figure 4. The lower ends of the side legs 14 are bent to provide horizontal rearwardly extending side bars 17 contacting with the 75 sides of the ski body and terminating in inwardly projecting extensions 18 adapted to be firmly secured in recesses formed in the ski. The forward end of the bracket frame is rigidly held in position by means of staples 19 embracing the lower ends of the side legs 14 and driven into the side of the 80 ski so as to maintain the bracket frame 13 in an upright vertical position transversely of the ski. With this construction, it will 85 be apparent that the transverse connecting bar 15 will be supported in an elevated position on the ski immediately forward of the foot pad 12.

90 Adapted for complementary connection 95 with the bracket member 13 and arranged for pivoted movement thereabout is a ground engaging spur 20 embodying a U-shaped body portion 21 looped at its ends to provide pivot ears 22 which are loosely fitted 100 about the transverse frame bar 15. The rear end portion of the spur 20 is formed to provide a pair of parallel laterally offset tines 23 bent to assume a downward angular position with respect to the longitudinal extension of the body portion 21 and having their lower ends tapered to form ground engaging points 24. It will thus be noted that the tines 23 of the spur are designed to extend at the sides of the ski body and spaced 105 110

slightly therefrom so that the rear pointed ends 24 will rest on the ground by force of gravity, while the **U**-shaped forward body portion of the spur is reduced in transverse extension so as to rest upon the side portions of the ski and thus limit the downward swinging movement with the spur when the ski assumes a position elevated from the ground. As indicated to advantage in Figures 4 and 5, the upward swinging movement of the spur is also restricted to a position slightly above the lower surface of the ski body by the tongue 16 formed on the support frame overhanging the transverse connecting bar of the spur body 21.

In use, as the ski is longitudinally slid over the ground in a forward direction the tines of the spur will drag on the ground at the sides of the ski body. When the forward stride is completed and the wearer proceeds to take a forward stride with the other ski the front ski will be held in position against backward slipping movement by the ground engaging action of the spur tines. In this manner it will be readily appreciated that the lost rearward motion of the skis is practically eliminated so that greater speed can be obtained and the skis may be used with diminished effort.

It is to be understood that the form of my invention herewith shown and described is to be taken as the preferred example of the same, and that various changes as to the shape, size and arrangement of parts may be resorted to without departing from the spirit

of the invention or the scope of the subjoined claims.

Having thus described my invention, I claim:

1. A ski attachment comprising an upright wire bracket secured on the intermediate portion of the ski body, a rearwardly extending tongue formed on the bracket and arranged at a downward inclination, a **U**-shaped spur having its forward portion pivotally connected with the bracket and its rear side portions offset laterally and pointed at the ends to normally engage the ground, the forward portion of the spur being adapted to engage the tongue of the bracket in an elevated position of the spur to limit the upward swinging movement thereof.

2. A ski attachment comprising an upright bracket rigidly attached to the ski body, a rearwardly projecting tongue formed on the intermediate portion of the bracket, and a substantially **V** shaped wire spur, the closed end of the spur being bent around the bracket so as to pivotally connect the spur to the bracket, the ends of the legs of the spur being pointed normally engageable with the ground to prevent back sliding movement of the ski, the closed end of the spur being arranged to engage the tongue formed on the bracket to limit the upward swinging movement of the spur.

In witness whereof I have hereunto set my hand.

CLEOPHAS DUMAIS.
